CLAIM

An ornamental design for an eyeglasses tag, as shown and described.

DESCRIPTION

FIG. 1 is a perspective view of an eyeglasses tag, showing my new design, a pair of eyeglasses being shown in broken lines for illustrative purposes only and forming no part of the claimed design;

FIG. 2 is an end elevation view, an opposite end elevation view being identical thereto;

FIG. 3 is a top plan view, a bottom plan view being a mirror image thereof; and,

FIG. 4 is a side elevation view, an opposite side elevation view being identical thereto.
